APPARATUS FOR ATTACHING SLIDE FASTENER LOCKING MEMBERS TO FLEXIBLE TAPES

Albert Süsskind, Berlin-Wilmersdorf, Germany

Application April 29, 1938, Serial No. 205,103
In Germany April 30, 1937

10 Claims.

(Cl. 153—1)

The invention is directed to improvements of slider fasteners. More particularly, the invention relates to a machine for producing locking members for so-called invisible slider fasteners.

5 This is the type of slider fasteners of which the locking members are invisible from outside so that the pair of adjoining flexible tapes appear to be sewn together. Each of these locking members is clamped round the known bulbed 10 edge of flexible tapes in such a way as to completely embrace this bulbed edge.

According to the invention, it is possible to attach the locking members, when being formed from a metal blank, to the longitudinally moved 15 flexible tape. But the operation can also be effected in such a manner that, after having attached a desired number of locking members, for example fifty, the machine stops and only the flexible tape moves on along a predetermined 20 distance. Then the machine operates as before until another row of a predetermined number of locking members has been attached; then the flexible tape moves on separately so that parts 25 of the flexible tape without locking members alternate with parts of the flexible tape having locking members attached thereto.

However, the locking members may also be produced separately in the desired shape according to the invention and may then be attached to the flexible tape. According to the invention, it is important that one end of each locking member is bent round the bulbed edge 30 of the flexible tape so as to embrace the latter by more than 180°, no additional holding means 35 being provided on the outer side.

In the accompanying drawing, several embodiments of the invention are illustrated by way of example, which are also described in the description, but it will be understood that the 40 description and the illustrations are merely for the purposes of explanation and that various other forms are possible within the scope of the invention.

In the drawing:

45 Fig. 1 is a view with partial section through the guiding or shaping block for producing the locking members from wire or flat material with the clamping arrangement.

Fig. 2 is a side view of the device, whereas 50 Figs. 3 and 4 are views of details.

According to the embodiment illustrated in Figs. 1 to 4, a continuous wire or flat strip 1 passes through the block 2. As will be seen from Fig. 2, a stamping die 3 and a cutting die 4 are 55 arranged in this block. The stamping die 3

stamps the projection or the recess 5 in the foremost piece of wire, which is cut off by the cutting die 4. The abutment for clamping this piece of wire with its lower end round the bulbed edge of the flexible tape is formed by the 5 face area 6 of the block 2. The flexible tape 7 being provided with the bulbed edge 8, round which the locking member 1' is to be clamped, is guided by a lever 9 under the action of a spring and tensioned at a certain distance from 10 the block, as shown in Fig. 1. Just before the free end of the section 1' is clamped round the bulbed edge 8 of the flexible tape 7, the lever 9 moves towards the block into the position shown by dotted lines in Fig. 1 so as to press the bulbed 15 edge 8 of the flexible tape 7 against the side of the section 1'. At the bottom of the block 2 on a bracket 10 there is a pressing jaw 11 which is oscillatable about the pivot 12. It has a circular shape 13 corresponding with the final 20 shape of the bent locking member. When the flexible tape is in the position shown by dotted lines in Fig. 1 owing to the moving of the lever 9, the jaw 11 is lifted and bends the lower end 25 of the section 1', which forms the clamping portion, round the bulbed edge 8 of the flexible tape 7 in the position also shown by dotted lines in Fig. 1. Now, the jaw 11 swings back and the lever 9 returns to its initial position shown in continuous lines in Fig. 1. The flexible tape is 30 thereby moved back from its position shown in Fig. 1, at the same time drawing out the portion of the attached locking member sticking in the block, the flexible tape with the attached locking member now being shifted by one space. 35

The order of the described operations can be arranged as desired. The driving means are not illustrated or described, as their construction and application is known.

Fig. 3 shows a special bifurcated form of the 40 grip of the lever 9 having an end portion 9''' for completely embracing the bulbed edge 8.

Fig. 4 shows a special form of the lever 9 with two arms 9' and 9''. The arm 9' has a width 45 somewhat smaller than the distance between the locking members 1', whereas the arm 9'' can be of any desired width. The thickness of the lever 9 must be smaller than that of the locking member 1' so that the jaw 11 can press the locking members round the bulbed edge 8 of the 50 flexible tape 7, without knocking against the arms 9' and 9''.

While the invention has been described with reference to specific structural details it will be appreciated that changes may be made therein 55

by those skilled in the art. Such changes may be made without departing from the spirit and scope of the invention as set forth in the appended claims.

5. What I claim is:

1. In a machine for attaching metal locking members to the bulbed edge of a flexible tape or stringer to form slider fasteners, a guiding and shaping block for producing locking members from strip metal of a suitable cross section, a rocking arm for holding said stringer at intervals in position in said block, a pivotable jaw adapted for bending the projecting end of said strip metal round said bulbed edge, means for shaping the locking member produced from said strip metal, and means for cutting off the shaped locking member from said strip metal.
10. 2. In a machine for attaching metal locking members to the bulbed edge of a flexible tape or stringer to form slider fasteners, a guiding and shaping block for producing locking members from strip metal of a suitable cross section, the block having a passage for the strip metal as well as transverse passages, a rocking arm for holding said stringer at intervals in position in said block, a pivotable jaw for bending the projecting end of said strip metal round said bulbed edge, means movable in one of said transverse 15 passages for shaping the locking member produced from said strip metal, and means for cutting off the shaped locking member from said strip metal.
20. 3. In a machine for attaching metal locking members to the bulbed edge of a flexible tape or stringer to form slider fasteners, a guiding and shaping block for producing locking members from strip metal of a suitable cross section, the block having a passage for the strip metal as well as transverse passages, the passage for the 25 strip metal leading into a recess in the block, a rocking arm for holding said stringer at intervals in position in said block, a pivotable jaw for bending the projecting end of said strip metal round said bulbed edge, means movable in one 30 of said transverse passages for shaping the locking member produced from said strip metal, and means movable in another of said transverse passages for cutting off the shaped locking member from said strip metal.
35. 4. In a machine for attaching metal locking members to the bulbed edge of a flexible tape or stringer to form slider fasteners, a guiding and shaping block for producing locking members from strip metal of a suitable cross section, a rocking arm for holding said stringer at intervals in position in said block, said rocking arm having a return spring, a pivotable jaw for bending the projecting end of said strip metal round said bulbed edge, means for shaping 40 the locking member produced from said strip metal, and means for cutting off the shaped locking member from said strip metal.
45. 5. In a machine for attaching metal locking members to the bulbed edge of a flexible tape or stringer to form slider fasteners, a guiding and shaping block for producing locking members from strip metal of a suitable cross section, a rocking arm for holding said stringer at intervals in position in said block, and said rocking 55 arm being bifurcated to embrace the bulbed edge of said stringer, a pivotable jaw for bending the projecting end of said strip metal round said bulbed edge, means for shaping the locking member produced from said strip metal, means for cutting off the shaped locking member from said strip metal, and said cutting means effecting a cut of a predetermined shape.
60. 6. In a machine for attaching metal locking members to the bulbed edge of a flexible tape or stringer to form slider fasteners, a guiding and shaping block for producing locking members from strip metal of a suitable cross section, a rocking arm for holding said stringer at intervals in position in said block, a pivotable jaw for bending the projecting end of said strip metal round said bulbed edge, means for shaping 65 the locking member produced from said strip metal, said shaping means stamping a recess in one side of the strip metal and a projection on the other side, and means for cutting off the shaped locking member from said strip metal.
65. 7. In a machine for attaching metal locking members to the bulbed edge of a flexible tape or stringer to form slider fasteners, a guiding and shaping block for producing locking members from strip metal of a suitable cross section, a rocking arm for holding said stringer at intervals in position in said block, a pivotable jaw for bending the projecting end of said strip metal round said bulbed edge, means for shaping 70 the locking member produced from said strip metal, means for cutting off the shaped locking member from said strip metal, and said cutting means effecting a cut of a predetermined shape.
75. 8. In a machine for attaching metal locking members to the bulbed edge of a flexible tape or stringer to form slider fasteners, a guiding and shaping block for producing locking members from strip metal of a suitable cross section, a rocking arm for holding said stringer at intervals in position in said block, a pivotable jaw for bending the projecting end of said strip metal round said bulbed edge, means for shaping 80 the locking member produced from said strip metal, means for cutting off the shaped locking member from said strip metal, and means for cutting off the shaped locking member from said strip metal.
85. 9. In a machine for attaching metal locking members to the bulbed edge of a flexible tape or stringer to form slider fasteners, a guiding and shaping block for producing locking members from strip metal of a suitable cross section, a rocking arm for holding said stringer at intervals in position in said block, a pivotable jaw for bending the projecting end of said strip metal round said bulbed edge, means for shaping 90 the locking member produced from said strip metal, said shaping means stamping a recess in one side of the strip metal and a projection on the other side, and partly widening the locking member, and means for cutting off the shaped locking member from said strip metal.
95. 10. In a machine for attaching metal locking members to the bulbed edge of a flexible tape or stringer to form slider fasteners, a guiding and shaping block for producing locking members from strip metal of a suitable cross section, a rocking arm for holding said stringer at intervals in position in said block, a pivotable jaw for bending the projecting end of said strip metal round said bulbed edge, means for shaping 100 the locking member produced from said strip metal, means for cutting off the shaped locking member from said strip metal, and said cutting means effecting a cut of a predetermined shape.

ALBERT SÜSSKIND.
